UNITED STATES PATENT OFFICE.

PHILIP D'H. DRESSLER, OF ZANESVILLE, OHIO, ASSIGNOR TO AMERICAN DRESSLER
TUNNEL KILNS, INC., OF NEW YORK, N. Y., A CORPORATION OF NEW YORK.

TUNNEL-KILN COMBUSTION-CHAMBER.

1,330,432.

Specification of Letters Patent. Patented Feb. 10, 1920.

Application filed May 28, 1919. Serial No. 300,444.

To all whom it may concern:

Be it known that I, PHILIP D'H. DRESSLER, a subject of the King of Great Britain, and resident of Zanesville, in the county of 5 Muskingum and State of Ohio, have invented certain new and useful Improvements in Tunnel-Kiln Combustion-Chambers, of which the following is a specification.

10 My present invention relates to combustion chambers of the kind used in the Dressler continuous tunnel kilns and the object of my invention is to provide a combustion chamber of this type having improved heat 15 transferring properties.

The various features of novelty which characterize my invention are pointed out with particularity in the claims annexed to and forming a part of this specification.

20 For a better understanding of the invention, however, and the advantages possessed by it reference should be had to the accompanying drawings and descriptive matter in which I have illustrated and de-

25 scribed a preferred embodiment of my invention.

Of the drawings:

Figure 1 is a diagrammatic plan of a kiln. Fig. 2 is an elevation in section on the 30 line 1—1 of Fig. 2.

Fig. 3 is a sectional elevation of one of the combustion chambers, the section being taken on the line 3—3 of Fig. 4.

Fig. 4 is a side elevation of a portion of 35 the combustion chamber shown in Fig. 3.

Fig. 5 is a view taken similarly to Fig. 4 showing another portion of the combustion chamber and

Fig. 6 is a plan view of the combustion 40 chamber portion shown in Fig. 3.

In the drawings I have shown my invention embodied in a continuous tunnel kiln of the general character shown in Patent No. 1,170,428 granted February 1, 1916, to 45 Conrad Dressler. In this type of kiln as shown in the drawings, the kiln chamber A proper is formed with a refractory wall B the upper portion of which is in the form of an arch. Benches B¹ are formed at the 50 base of the arch at opposite sides of the path for the goods carrying cars which run on track rails C. C. The kiln is heated by burning gaseous fuel in combustion chambers D mounted on the benches B¹. The

combustion chambers extend the major portion of the horizontally elongated kiln and at their outlet ends are connected to heat radiating pipes F ordinarily formed of iron which convey the partially cooled products of combustion to the end of the kiln chamber at which the entrance A¹ for the goods carrying cars is provided. Fuel is supplied to the combustion chambers at the ends of the latter adjacent the outlet A² for the goods carrying cars. As shown pipes H 65 extend from the outlet end of the kiln chamber to the adjacent ends of the combustion chambers D. The pipes H which are mounted on the benches B¹ form conduits for a cooling fluid. This cooling fluid may 70 be the air for supporting combustion in the combustion chambers which is thus pre-heated by its passage through pipes H. The walls of the combustion chambers D are formed of cellular bodies of refractory 75 material of the general character of hollow tile. As shown the wall for each combustion chamber is formed of bottom sections E, outer vertically disposed sections E¹, inner vertically disposed sections E³ and E³⁰, 80 and top sections E² and E²⁰. As shown the sections E, E¹, E², E³, E²⁰ and E³⁰ are all alike in that each is formed with three longitudinal air channels e. With this arrangement there is a continuous circulation 85 of the air or other gaseous atmosphere of the kiln chamber, upward through the channels e in the vertically disposed sections E¹, E³ and E³⁰. In its passage through the channels e, the air takes up heat from 90 the combustion chambers. The heated air issuing from the channels e in sections E² and E²⁰ at the top of the kiln chamber A passes down through the central portion of the kiln chamber in contact with the goods 95 to which it gives up some of its heat. The air, thus partially cooled, again enters the channels e of the bottom sections E of the combustion chamber walls, the circulation thus being continuous. In so far as above 100 described the structure illustrated does not differ from the construction heretofore made in general accordance with the disclosure of said prior Patent 1,170,428.

The circulation of air through the channels e of the wall of the combustion chambers D has been found to be a very valuable 105 feature in the kilns in which this type of

combustion chamber is employed, as it tends to equalize temperature conditions at the top and bottom of the kiln chamber, and avoids a local overheating of the goods which 5 would be apt to occur if the goods were directly exposed to radiation from the most highly heated portions of the combustion chamber walls. I have discovered however that the heat distribution in a kiln of this 10 general type may be materially improved in some cases by providing openings in the outer walls of the channels *e* of some of the wall sections of the combustion chamber. Thus as shown I form a series of openings 15 or windows *e*¹⁰ in the outer walls of the channel *e* of the sections *E*³ of the combustion chamber walls, said series extending practically from one end to the other of each section *E*³. Windows are similarly 20 formed in the top walls of the channels *e* of the sections *E*². Windows *e*¹⁰ are formed in the lower portions of the outer walls of the channels *e* in the sections *E*³⁰. No windows are formed in the sections *E*, *E*¹, and *E*²⁰. 25 As shown the sections *E*² and *E*³ are em- ed to form the portion of the combustion chambers *D* adjacent the outlet ends of the latter between the transverse planes indicated by the lines 10-10 and 20-20. 30 The sections *E*²⁰ and *E*³⁰ form the tops and inner sides of the combustion chambers between the plane indicated by the lines 20-20, and the inlet ends of the combustion chambers. The effect of providing windows *e*¹⁰ 35 in the lower portion of the section *E*³⁰ is to increase the temperature at the bottom of the kilns slightly in the high temperature zone of the kiln which otherwise has a tendency to be slightly hotter at the top 40 than at the bottom. The purpose of providing windows *e*¹⁰ all along the inner sides and top portions of the combustion chamber walls adjacent the outlet ends of the combustion chambers is primarily to in- 45 crease the heat transfer from the combustion chambers to the goods in this portion of the kiln thereby increasing the effectiveness of the kiln by taking more of the heat away from the products of combustion before the latter pass into the pipes *F*. The 50 provision of the windows *e*¹⁰ and the heat radiation which takes place through them does not prevent the channels *e* in the walls of which the windows are formed, from 55 performing their intended function of providing an effective convection current flow of air upward past the combustion chambers and downward through the space traversed by the goods nor do these windows 60 deprive the combustion chamber walls in which they are formed from having the heat resisting properties arising from the fact that the walls of the channels *e* adjacent the combustion chambers proper may soften 65 without the deformation of the walls sec-

tion since the shape of the latter is pre- served by the cooler unsoftened outer por- tions of the walls of the channels *e*.

While in accordance with the provisions of the statutes I have illustrated and de- 70 scribed the best form of my invention now known to me it will be apparent to those skilled in the art that changes may be made in the form of the apparatus disclosed with- out departing from the spirit of my in- 75 vention as set forth in the appended claims and that certain features of my invention may sometimes be used to advantage with- out a corresponding use of other features.

Having now described my invention, what 80 I claim as new and desire to secure by Let- ters Patent, is:

1. As a new article of manufacture a com- 85 bustion chamber wall section having an air circulatory passage lying between its inner and outer wall surfaces and open at its ends and a window opening from said passage to the outer wall surface of the section.

2. As a new article of manufacture, a com- 90 bustion chamber wall section having open ended air circulatory passages lying between and parallel to its inner and outer wall sur- 95 faces and windows opening from said pas- sages to the outer surface of the wall sec- tion.

3. In a tunnel kiln comprising a kiln chamber and an elongated combustion cham- 100 ber therein said combustion chamber being formed with walls having air circulatory passages therein open to the kiln chamber proper at levels adjacent the top and bottom of said chamber, the improvement which consists in windows formed in the outer walls of said channels whereby heat is trans- 105 mitted from the combustion chamber both by convection currents and by radiation through said windows.

4. In a tunnel kiln comprising a kiln chamber and an elongated combustion cham- 110 ber therein at the sides of a goods receiving space in said kiln chamber said combustion chamber being formed with walls having air circulatory passages therein open to the kiln chamber proper at levels adjacent the top and bottom of said chamber, the improve- 115 ment which consists in windows formed in the outer walls of said channels and facing the goods receiving space.

5. In a tunnel kiln comprising a kiln chamber and an elongated combustion cham- 120 ber therein at the sides of a goods receiving space in said kiln chamber said combustion chamber being formed with walls having air circulatory passages therein open to the kiln chamber proper at levels adjacent the top and bottom of said chamber, the improve- 125 ment which consists in windows formed in the outer walls of said channels and facing the adjacent portion of the kiln chamber wall.

6. In a tunnel kiln comprising a kiln chamber and an elongated combustion chamber therein at the sides of a goods receiving space in said kiln chamber said combustion chamber being formed with walls having air circulating passages therein open to the kiln chamber proper at levels adjacent the top and bottom of said chamber, the improvement which consists in windows formed in the outer walls of said channels and facing the lower portion of the goods receiving space along a relatively high temperature portion of the combustion chamber and facing the goods receiving space and a portion of the upper wall of the kiln chamber along a relatively low temperature portion of the combustion chamber.

Signed at city of Zanesville, in the county of Muskingum and State of Ohio this 19th day of May, A. D. 1919.

PHILIP D'H. DRESSLER.
